(57) **CLAIM**

The ornamental design for a pacifier lollipop, as shown and described.

DESCRIPTION

FIG. 1 is a perspective view of the pacifier lollipop showing my new ornamental design;

FIG. 2 is a front elevational view thereof;

FIG. 3 is an elevational view of one side thereof;

FIG. 4 is a top plan view thereof;

FIG. 5 is a bottom plan view thereof; and,

FIG. 6 is a perspective view of an alternative embodiment, similar to that shown in FIG. 1 but without the handle, the top plan view being identical to that of FIG. 4 and the front and side elevational views being essentially the same as those of FIGS. 2 and 3 but without the handle, the sidewall of the cylindrical piece below the heart shaped guard being plain and unornamented, and the bottom plan view being essentially the same as that of FIG. 5 but without the handle, the circular bottom wall of the cylindrical piece below the heart shaped guard being plain and unornamented.
